CLAIM

The ornamental design for a top band for an article of hosiery, as shown and described.

DESCRIPTION

FIG. 1 is a perspective view of an article of hosiery showing an embodiment of our invention;

FIG. 2 is a side plan view thereof, the opposite side being a mirror image thereof;

FIG. 3 is a rear perspective view thereof; and,

FIG. 4 is a sectional view taken along line 4—4 of FIG. 1. The broken lines shown herein are for illustrative purposes only and form no part of the claimed design.

1 Claim, 3 Drawing Sheets

FIG. 1.

FIG. 2.
